(57) CLAIM

I claim the ornamental design for a lighted hat, as shown and described.

DESCRIPTION

FIG. 1 is a perspective view of the lighted hat according to my new design;

FIG. 2 is a right side elevational view of the lighted hat of FIG. 1;

FIG. 3 is a top plan view of the lighted hat of FIG. 1;

FIG. 4 is a left side elevational view of the lighted hat of FIG. 1;

FIG. 5 is a front elevational view of the lighted hat of FIG. 1;

FIG. 6 is a rear elevational view of the lighted hat of FIG. 1; and,

FIG. 7 is a bottom plan view of the lighted hat of FIG. 1.
